PEBBLE HEATING CHAMBER

Sam P. Robinson, Bartlesville, Okla., assignor to
 Phillips Petroleum Company, a corporation of
 Delaware

Application July 20, 1948, Serial No. 39,709

6 Claims. (Cl. 263—19)

1

This invention relates to an apparatus for heating pebbles. In one of its more specific aspects, it relates to an improved apparatus for heating a contiguous moving mass of pebbles.

Many processes used in industry today, particularly those wherein the constituents are gaseous, require high temperatures to enable them to operate at maximum efficiency or to be operable at all. Several different types of apparatus have been used with varying success. One particular type highly suited to heating gases to such temperatures as 2000 to 3000° F. or of course, to lower temperatures, is the pebble heater. Generally, this apparatus is constructed primarily of refractory bricks contained within an outer metal shell. The construction is such that a contiguous mass of pebbles may be passed through and exposed to hot gases. The design is made so that the pebbles will pass through the heater in an even flow, that is, the pebbles at the side of the chamber pass through at the same rate as those toward the center; and so the pebbles will be evenly heated. Some of the processes which may utilize a pebble heater to particular advantage, to name just a few, are cracking of hydrocarbons, synthesis gas (H₂ plus CO) generation, and super-heating of steam.

In most processes using pebble heaters, the pebbles are first heated in a conventional heater and then passed by gravity, utilizing suitable control apparatus, to a reaction chamber situated below the heater. The material, or materials, to be heated are introduced to this chamber under suitable pressure conditions so that there will be no flow of hot gases from the heater to the reaction chamber, and only a slight flow of reactants into the heater. By so controlling the pressure, the materials within the reaction chamber remain uncontaminated. The speed of pebbles which flow in a contiguous mass through the heater and the reaction chamber is controlled to give the desired temperature within the reaction chamber.

The term "pebbles" as used herein refers to refractory elements which form a fluent, particulate mass. These pebbles are preferably substantially spherical and relatively uniform in size, but may be rod shaped or irregular in shape or size. Spheres of about $\frac{1}{8}$ inch to 1 inch in diameter are suitable and those of $\frac{1}{4}$ inch to $\frac{1}{2}$ inch diameter are preferred. Care must be taken to select pebbles of proper composition for a given process. In cracking organic materials at elevated temperatures, pebbles of highly refractory character and ruggedness must be uti-

2

lized. In conducting endothermic reactions at elevated temperatures, it is important to operate with pebbles of relatively high specific heat in order to introduce sufficient heat to the conversion chamber with a minimum flow of pebbles. Pure alumina pebbles fired at temperatures between 3000 and 3500° F. are suitable for many hydrocarbon conversion processes. Pebbles comprising beryllia, silicon carbide, mullite, periclase, and zirconia make excellent contact materials for some processes. Pebbles of the materials above named may be impregnated with other materials which are catalytic in nature, but this treatment usually renders them less suitable for use at extremely high temperatures such as 2500° F. and higher. Metal balls such as nickel, monel, inconel, iron, copper, etc., have utility in specific processes. Various adsorbent materials such as silica gel, active aluminas, activated carbon, etc., have wide utility in gas treatment and adsorption.

An object of this invention is to provide an apparatus for contacting gases and solids in countercurrent flow which permits substantially uniform contact time throughout the bed of solids.

Another object of this invention is to provide a gas-solid contact chamber in which hot gases are generated therein.

Another object of the invention is to provide apparatus for contacting gases and pebbles which assures substantially even distribution of gases throughout the mass of pebbles.

Another object is to provide apparatus for contacting hot gases and pebbles which includes a tempering bed to insure a more even temperature throughout the mass of pebbles.

Another object is to provide an apparatus for uniformly heating a mass of pebbles in which is located a hot gas generating chamber supported from the top of the pebble heater by hollow supporting members through which may be circulated a suitable coolant.

Another object of this invention is to provide apparatus for utilizing a minimum of heat to heat a mass of pebbles.

Further objects and advantages of this invention will be apparent to one skilled in the art from the accompanying disclosure and discussion.

In the operation of apparatus constituting a preferred embodiment of this invention, pebbles to be heated are passed from a reservoir through a plurality of evenly spaced inlet means into the top of an annular space formed between the inner surface of the pebble heater shell and the

outer surface of the heat-generating chamber which is axially positioned within the pebble heater. The heat-generating chamber is formed by hard-burned abrasion-resistant brick and burner tile built around and supported by metal pipes attached to a nose ring and through which is circulated a suitable coolant. In addition the chamber is supported from the top of the pebble chamber by the metal pipes. The arrangement of the brick and tile is such that a minimum of gas will pass therethrough. Examples of such construction are shown in the attached drawings which are discussed below. However, these drawings should not be interpreted as limiting the scope of my invention, but rather as particular examples of it. In a preferred embodiment of this invention, the heat-generating chamber extends through the top of the pebble heater shell, although it is within the scope of my invention to have this chamber extend from the top of the shell or to be located entirely within said shell. Within the broad aspect of my invention, the heat-generating chamber may be supported by means other than the metal pipes described above, such as solid metal rods or other suitable means. However, when utilizing my apparatus to heat pebbles to the high temperatures within the scope of my invention, it is preferred to use hollow pipes of one type or another through which may be circulated a suitable coolant. In any modification of my invention, the heat-generating chamber should be axially positioned and supported by or from the top of the shell so that the lower open end thereof forms a relatively narrow annular space between said end and the wall of the frusto-conical lower portion of the pebble heater shell. This arrangement provides more uniform heating of the pebbles with maximum efficiency. As the pebbles pass downward in a contiguous mass they are heated by radiation and conduction through the walls of the heat-generating chamber as well as by the hot gases which pass through them in counter-current flow.

The portion of the pebble heater which extends below the mouth of the heat-generating chamber is a tempering area or bed where the pebbles are allowed to remain sufficiently long for the temperature to become relatively even throughout. From the tempering bed the pebbles pass through what is known as a pebble throat located at the bottom of the tempering bed and from there to whatever use it is desired to make of them.

A modification of my invention is to introduce hot gases such as refinery flue gases into the heat-generating chamber. In any case, the hot gases generated within or without the pebble heater are passed downward through the heat-generating chamber and out the open lower end into the gas space formed by said end and the pebble bed thereunder. The gases pass from the gas space upwardly through the pebbles and into another gas space located just below the top of the pebble heater shell. From here, they are removed by suitable means such as one or more flues.

A further understanding of some of the many aspects of my invention may be had by referring to the accompanying drawings in conjunction with the following discussion.

Figure 1 is a vertical cross-section of one specific embodiment of my invention partially cut away. Figure 2 is a horizontal cross-section of the pebble heater shown in Figure 1 taken along

line 2-2 which shows the positioning of the pebble inlets and the heat generating chamber. Figure 3 is a horizontal cross-section also of the pebble heater shown in Figure 1 taken along line 3-3 and shows the manifold for passing coolant through the supports for the heat generating chamber. Figure 4 is an enlarged cut away isometric view of a portion of the nose ring of the heat generating chamber shown in Figure 1 which shows one method for suspending the abrasion resistant brick and burner tile on the nosed ring and around the vertical piping which supports the nose ring. Figure 5 is a vertical cross-section of Figure 4 taken along line 5-5 and shows again the way in which the tile and brick are suspended on the nose ring. Figures 6 and 7 show two examples of brick and tile construction which may be used to prevent gas passage through the heat generating chamber.

Refer to Figure 1 which is a vertical cross section of one embodiment of my apparatus. Numeral 10 indicates the outer shell of the pebble heater which includes a vertical shell closed at either end, the top 11 of said shell being in the shape of a dome and the bottom 15 of said shell being in the shape of a frustum of an inverted cone wherein the angle of convergence of the sides is preferably less than 60°. Number 12 indicates the pebble throat. Number 13 indicates the heat-generating chamber which extends through the top dome of the shell.

Number 14 is the metal outside structural support of the heater. Number 16 is the hard-burned abrasion-resistant ceramic brick insulating lining of the vertical shell, frusto-conical section, and pebble throat. Numeral 17 is the insulating cement portion of the top of the pebble heater.

Number 26 is a pipe for introducing cooling material to manifold 24 from which it passes through pipes 23 to nose ring 22. Number 21 are outlet pipes which carry the cooling material from the nose ring to manifold 28 from which it is removed through pipe 18. It is, however, within the scope of this invention to pass the coolant in opposite directions to that indicated as may be desirable under certain conditions, particularly if the cross-section area of the inner pipe is greater than the cross-section of the annular space between the inner and outer pipe. Number 27 is a ring of hard-burned abrasion-resistant bricks so fashioned that the bricks completely encompass the nose ring and are supported by same as shown in Figures 5 and 7 of this specification discussed below. Number 28 indicates burner tile which are so arranged as to form the body of heat generating chamber 13. These tile are so constructed that they fit around tubes 21 to protect them from direct heat. Number 29 indicates a Venturi tube in the burner throat of the heat-generating chamber which aids in mixing the combustion materials. Number 30 indicates insulating brick which close the upper end of the heat-generating chamber and through which extends burner 31 to which is attached nozzle 35. Numeral 32 indicates a pair of flanges bolted together so that the burner and nozzle may be removed for cleaning or replacement. Pipes 33 and 34 are inlet means to burner extension 36 for fuel and air.

Reservoir 37 is for pebbles to be heated. Said pebbles are passed through pipes 38 which pass through the top of the heater and into the upper portion of annular space 39 formed between

heat-generating chamber 13 and the outer heater shell 10. The hot gases which are generated in chamber 13 pass out its lower end, up through the annular space, and out stack, or stacks, 40 located at the top of said annular space.

Figure 2 is a horizontal cross-section of the pebble heater shown in Figure 1 at line 2—2. The same parts of this drawing as are shown in Figure 1 will be similarly numbered. The metal shell supporting the pebble heater is indicated at 14. Numeral 16 is the hard-burner abrasion-resistant brick lining of the pebble heater. Number 38 indicates inlet pipes for pebbles to annular space 39. Number 13 indicates the heat-generating chamber comprised of burner tile 28. Numbers 21 and 23 show outlet and inlet pipes for cooling material. Number 25 indicates the inner surface of pebble throat 12.

Figure 3 is a top view of the pebble heating chamber shown in Figure 1 taken at line 3—3. As in Figure 2 parts of this drawing identical to parts in Figure 1 are identified by the same number. Number 10 indicates the periphery of the pebble heater. Number 38 indicates the pebble inlets as previously indicated in Figures 1 and 2. Pipes 33 and 34 are inlet means for fuel and air to burner extension 36. Pipe 26 is an inlet means for cooling material to manifold 24. Pipe 18 is a cooling material outlet means for manifold 20. Number 32 is a pair of flanges attached to burner extension 36 which is bolted to the burner flange below with bolts 42. The hot gas exhaust stack is indicated at 40.

Figure 4 is an enlarged cutaway perspective view of a portion of the nose ring of the heat-generating chamber. As in the other drawings, those parts which correspond to identical parts shown in Figure 1 are similarly numbered. This drawing shows the assembly of the first row of brick at the mouth of the chamber and the means for supporting same. It also shows the arrangement of the burner tile, how they fit around the cooling pipes, and ridges and grooves for retarding the passage of hot gases through them. Number 22 is the hollow nose ring to which are attached the individual cooling members 21 which also support the chamber. These cooling members are attached by welding to the nose ring where a hole has been cut out substantially the size of the cooling pipe so that material used for cooling may be passed into the nose ring. Number 23 is the inlet cooling pipe which extends into the nose ring. Numbers 27 and 28 are hard-burned abrasion-resistant brick and burner tile, respectively. Number 43 is a means for supporting the lower ring of brick which in turn supports the rest of the burner tile comprising the heat-generating chamber. As shown here it is an inverted channel iron, the bottom of which has been creased or bent downward sufficiently to keep the brick from falling or being pushed off. A more clear idea of this may be had by referring to Figure 5 which is a vertical cross-section taken at 5—5 of Figure 4. This drawing shows the design of brick 27 which are so constructed that they will fit on channel iron 43 and surround nose ring 22. Further, the more pressure applied to the top of bricks 27 the better they will fit together, because the design of the flange upon which they rest is such that the bricks tend to slide toward each other. This pressure would be that of additional layers of brick and tile forming the upper portion of the heat-generating chamber.

This drawing also shows how pipe 23, which is the inlet means for the coolant, protrudes into the nose ring. Numerous coolants may be used for circulation through the pipes in the heat-generating chamber, depending upon the temperature at which the apparatus is to be operated. Water is a very satisfactory coolant for high temperatures because of the heat it removes on vaporization. Other suitable coolants are 10 mercury, and "Dowtherm" (a mixture of diphenyl and diphenyl oxide). It may also be advantageous to utilize inert gases as coolants. In general, any material will be satisfactory as a coolant if it will remove sufficient heat, and will not decompose in the pipes leaving a deposit or react with the pipes.

Figures 6 and 7 merely give two examples of burner tile construction of the heat-generating chamber to prevent gas passage between the individual tile. Similar grooves and ridges to those shown in Figure 6 are shown also in Figure 4. In both drawings, number 23 indicates one of the inlet means for cooling material and number 21 indicates one of the outlet means for cooling material.

It is within the scope of my invention to suspend the heat-generating chamber by other means than those shown in the above described drawings. For example, rather than having one pipe within the other, only one pipe may be used at each place. Thus every other pipe would pass coolant down to the nose ring through which it would pass to the next pipe on each side and be removed therethrough. Other means for suspending the heat-generating chamber through which may be circulated a suitable coolant are also within the scope of my invention.

There are many advantages attained in utilizing my pebble heating apparatus. Foremost among them are increased heat transfer capacity and thermal efficiency by having the heat-generating chamber located within the pebble heater and reduction in over-all weight obtained by eliminating interior supports for the heat-generating chamber. Two other important advantages are reduction in construction cost by the simplicity of the apparatus, and better performance with less maintenance required. Other specific improvements of my apparatus over the art are: no static pebble zones exist because all the walls are steeper than the angle of rest of submerged pebbles under load; all pebbles must pass through the zone exposed to hottest combustion gases; flow of pebbles to the single pebble outlet or throat is unrestricted; the pressure drop is relatively low because of less restriction to flow of the hot gases; and lessening of the requirement of thick walled insulating fire brick protection for the shell. My apparatus provides high capacity, cheap, light, and simple construction.

Although this apparatus has been described in terms of its preferred modifications, it is understood that various changes may be made without departing from the spirit and scope of the disclosure and of the claims.

I claim:

1. An apparatus for imparting heat to material, which comprises a vertical metal shell, a top member, an axially positioned heat-generating chamber constructed of burner tile supported by a bottom ring of hard-burned abrasion-resistant brick, vertical hollow members supporting said tile and said brick and enclosed within same and through which may be passed cooling ma-

terial, means for supporting said vertical hollow members from the top of said shell, said chamber extending downwardly through said top member and terminating in a freely open lower end, a ceramic brick lining for said shell, said chamber and said shell forming an annular space for containing material to be heated, a plurality of inlet means for introducing said material into the top of said annular space, outlet means for said heated material in said bottom member, means for causing flow of hot gases through said heat-generating chamber and out said freely open end thereof into said annular space, and gas outlet means leading from the top of said shell whereby said hot gases passing upwardly through said annular space to heat said material therein and thence into said gas outlet means are exhausted.

2. An apparatus for heating a downwardly flowing contiguous mass of pebbles, which comprises a vertical shell comprising an upper cylindrical portion and a lower frusto-conical portion and composed of at least an outer metal support and an inner ceramic brick lining, a top member for said shell, an axially positioned ceramic brick heat-generating chamber extending downwardly through and supported by said top member and terminating in a freely open end at a point within said shell above the bottom thereof and below the upper limit of said frusto-conical portion and forming with said shell an annular space for containing a downwardly flowing contiguous mass of pebbles to be heated, the space within said frusto-conical portion below said freely open end of said heat-generating chamber comprising a tempering zone for said pebbles, a plurality of inlet means for introducing pebbles into said annular space, outlet means for said heated pebbles at the bottom of said shell forming a pebble throat, means for causing flow of hot gases through said heat-generating chamber and out said freely open end thereof into a gas space created at the bottom of said chamber by said freely open end and said contiguous mass of pebbles, and gas outlet means leading from the top of said shell whereby said hot gases passing upwardly through said annular space to heat said pebbles therein and thence into said outlet means are removed.

3. An apparatus for heating a downwardly flowing contiguous mass of pebbles, which comprises a vertical steel shell, the bottom member of said shell forming a frustum of an inverted cone, the top member of said shell forming a dome, said dome being lined with insulating concrete, an axially positioned heat-generating chamber constructed of burner tile supported by a bottom ring of hard-burned abrasion-resistant brick, said tile and brick being fabricated so as to inhibit the passage of gas therethrough, and hollow members enclosed within said tile and brick and supporting same through which may be passed cooling material, said chamber extending downwardly through and supported by said top member and terminating in a freely open lower end at a point within said shell and above the bottom of and substantially below the upper limit of said frustum, a ceramic brick lining for said shell, said chamber and said shell forming an annular space for containing a downwardly flowing contiguous mass of pebbles to be heated,

the space within said frustum of an inverted cone extending below said freely open end of said heat-generating chamber comprising a tempering zone of said pebbles, a plurality of inlet means for introducing pebbles into the top of said annular space concentrically positioned to provide a uniform contiguous mass of pebbles within said annular space, outlet means for said heated pebbles at the lower end of said bottom member forming a pebble throat, means for causing flow of hot gases through said heat-generating chamber and out said freely open end thereof into a gas space created at the bottom of said chamber by said freely open end and said contiguous mass of pebbles, and gas outlet means leading from the top of said shell whereby said hot gases passing upwardly through said annular space to heat said contiguous mass of pebbles therein and thence into said gas outlet means are removed.

20 4. An apparatus according to claim 2 wherein said plurality of inlet means for said pebbles to said annular space are concentrically positioned in relation to said heat-generating chamber and said vertical shell, and centrally located between said chamber and said shell.

5. An apparatus according to claim 2 wherein the angle of convergence of the sides of said frusto-conical portion is less than 60 degrees.

6. An apparatus according to claim 3 wherein 30 said heat-generating chamber is cylindrical and comprises a burner throat at the upper end thereof, inlet means to said throat through which may be passed fuel and air, a horizontal hollow supporting nose ring member, a plurality of vertically positioned hollow members radially positioned about the axis of said chamber and spaced equidistant from each other and each comprising two concentric hollow members, said vertical members supporting said nose ring and being attached to same in such a manner that a coolant 40 may be passed downwardly through the inner members into said nose ring and upwardly through the outer members, means for introducing a coolant to said inner members, means for withdrawing said coolant from said outer members, hard-burned abrasion-resistant bricks supported by and enclosing said nose ring, burner tile forming the body of said heat-generating chamber and enclosing said vertically positioned hollow members, and means for supporting said vertically positioned hollow members.
